Application May 13, 1954, Serial No. 429,556

8 Claims. (Cl. 30—228)

This invention relates to pruning or tree-lopping shears and, more particularly, it relates to power-operated shears which operate smoothly and effectively and which are less costly and easier to manipulate than prior shears of this type.

Prior power-operated lopping shears have generally required the use of expensive auxiliary equipment and have accordingly involved high maintenance costs. A particular disadvantage of such prior power shears is weight of the actuating mechanism for the shears, which weight must be continuously borne by the operator as he manipulates the tool from one cutting position to the next. Such prior shears also tend to jolt or jar unless deliberately operated slowly and at low power or pressure. Such jolting or jarring is tiring and aggravates the energizing effect of continuously manually supporting the weight of the actuating mechanism.

We have provided a power shear of the type described which operates from any tractor power take-off, thus avoiding the original cost and maintenance expense of hydraulic or pneumatic compressors and the like. A particular advantage of the invention is that the weight of the cutting end is minimized because the shear actuating or driving means is supported directly on the base frame or bed of the mechanism. Further, the operation is such that there is no jolting or jarring when the shears are actuated; in fact, the operation is so smooth that, unless the operator watches the actual cut, it is difficult for him to determine whether he is trimming wood rather than cutting through empty air.

These and other objects and advantages of the invention will become apparent from the following description of one specific embodiment of the invention, together with the accompanying drawings, in which:

Figure 1 is a side view of an actuating drive used in the illustrated embodiment of the invention.

Figure 2 is an end view of the mechanism shown in Figure 1.

Figure 3 is a section taken on line 3—3 in Figure 1.

Figure 4 is a section taken on line 4—4 in Figure 1.

Figure 5 is a view of a shearing head used in the illustrated embodiment of the invention.

Figure 6 is a view in cross-section and on an enlarged scale showing one of the details of the structure illustrated in Figure 5.

Figure 7 is a view in cross-section on a still larger scale showing another detail of the structure illustrated in Figure 5.

As shown in the drawings, the base or frame of the mechanism may comprise suitable channels 10 adapted to be rigidly mounted with standard U-bolts to a tractor draw bar and having their outer ends joined by a plate or bed 11. A support 12 extends from the base or frame and adjustably supports a bearing block 13 which, in turn, supports the free end of a power take-off extension shaft 14 which is splined to the power take-off shaft 15 of the tractor on which the unit is mounted. The extension shaft 14 may include a universal coupling 16

to compensate for any misalignment with the power take-off shaft 15.

The bearing blocks 19 and 20 on the plate 11 support the shaft 22 which extends through a standard one-revolution clutch which may be of the Hilliard type, the clutch being generally indicated at 23. The clutch sprocket 24 is coupled by a chain 25 to a drive sprocket 26 keyed to the extension shaft 14. The trip lever 27 (see Figure 3) of the clutch is coupled by a link 28 to an actuating 10 solenoid 29, the lever 27 being biased into normally extended clutch deactivating position by the spring 30.

The shaft 22 is coupled to a shaft 31 through the spur gears 32 and 33, the shaft being mounted between the bearing blocks 20 and 34. The gear ratio through this 15 coupling is preferably 1:2 for reasons which will appear below. Keyed on the shaft 31 is a hold-out cam 35 (see Figure 4) which is engaged by a cam follower arm 36 mounted on a small shaft 37 which is mounted on the base of the block 20 and which carries at its opposite 20 end a bell crank 38 (see Figure 3). The bell crank 38 is coupled to the clutch trip lever 27 by a connecting link 39. The bias of the spring 30 keeps the follower arm 36 in following engagement with the hold-out cam 35.

An outrigger support arm 45 extends from the frame 25 or base of the mechanism. A slotted anchor plate 46 fixed to the outer end of the arm 45 supports a push-pull cable unit comprising an outer flexible sheath 47 and an inner push-pull cable 48. At the anchor plate 46, the sheath 47 terminates in a sleeve 49 which is threaded 30 engaged and clamped in position by the mounting nuts 50. The end 51 of the sleeve 49 comprises the socket half of a ball and socket joint. The suitably formed end of a sleeve 52 forms the ball half of the ball and socket joint. The sleeve 52 is received in a sleeve 53 in which it slides in telescoping engagement. The sleeve 53 is fixed to the terminal fitting of the cable 48 which, in turn, is fixed to a terminal link 54. The terminal link 54 is pivoted to a drive crank 55 keyed on the end of the shaft 31.

40 The push-pull cable unit comprising the outer flexible sheath 47 and the inner push-pull cable 48 may extend any desired distance to the shearing head shown in Figure 5, a good working length being about 20 feet. The housing or handle of the shearing head may comprise coaxial

45 tubes 60 and 61 which are joined by a swivel connection indicated at 62. Figure 7 is a fragmentary section taken in the plane of the paper in Figure 5 in the vicinity of the swivel connection 62. Flanged end inserts 63 are fixed in the ends of the tubes 60 and 61, the flanges being held in sliding abutting relation by a split collar 64 which is held in clamping position by the bolts 65 (Figure 5).

50 The sheath 47 terminates in a sleeve 66 which is threaded 55 engaged with a pair of nuts 67 which are tightened against an endplate 68. The endplate fits through transverse slots cut on opposite sides of the tube 60, the endplate center being notched to accommodate the portion of the tube 60 between the transverse slots. The cable 48 extends through the sleeve 66 and is anchored to a rod 69 which extends through the tube 60 and swivel connection 62 and is bolted to a stiff strap 70. At the opposite end of the strap 70, an actuating rod 71 is fixed by a ball bearing swivel connection shown in detail in Figure 6. The outer raceway sleeve 72 is held in seated position against the end of the strap 70 by a ring 77 welded 60 to the strap as shown. The inner raceway sleeve 73 is clamped between the nuts 74 which are anchored by the locking nuts 75 as shown. Relatively light compressive loads may be carried through the split retaining ring 76 or directly from the outer nut 74 to the end of the strap 70, depending on the length of the inner raceway sleeve 73.

The opposite end of the actuating rod 71 passes out

the end of the tube 61 and is linked to the pivoting knife of the shear. The fixed knife of the shear is mounted beyond the end of the tube 61 as shown in Figure 5.

Mounted on the tube 60 is a switch 80. The switch leads 81 are secured along the sheath 47 by suitable clamps. The leads 81 are in a circuit from the tractor battery to the switch 80, then to the solenoid 28 and then to ground on the frame of the mechanism, as clearly indicated in Figure 1. The leads 81 may be provided with quick disconnects 82 and may be enclosed in a common jacket as indicated at 83.

At the idling speed of an average tractor, momentary closing of the switch 80 will cause the mechanism to complete one cutting cycle in approximately one second, which provides a desirable cutting speed. Naturally, slight variations in tractor R. P. M. may be made if desired in order to obtain a corresponding change in cutting speed. For example, doubling the tractor R. P. M. will cause the unit to complete a cutting cycle in approximately one-half second, this faster cutting rate being preferable in many instances.

The clutch sprocket 24 is constantly driven through the directly coupled linkage leading from the tractor power take-off 15. When the switch 80 is closed, the solenoid 28 is actuated and momentarily withdraws the trip lever 27. The clutch is thereupon released to transmit power from the sprocket 24 to the shaft 22. The shaft 22 drives the shaft 31 through the spur gears 32 and 33. As the shaft 22 completes one revolution, the cam follower arm 36 is engaged with the high portion of the cam 35, thus holding the trip lever 27 in withdrawn position to release the clutch for an additional revolution of the shaft 22. On the completion of the second revolution of the shaft 22, the shaft 31 completes one full revolution, the cam follower arm 36 is in engagement with the low portion of the cam 35 having thereby allowed the trip lever 27 to be urged into clutch engaging position by the spring 30, and power transfer from the sprocket 24 to the shaft 22 is thereupon terminated as the radial face of the clutch trip cam 30a contacts the trip lever 27.

During the single revolution of the shaft 31, the cable 48 is reciprocated through one pull-push cycle by the drive crank 55. Any tendency of the throw of the drive crank 55 to cause whipping of the push-pull unit is overcome by the rigid non-pivoting mounting of the sleeve 49 on the anchor plate 46, lateral throw of the driven end of the push-pull unit being accommodated by the ball and socket joint at 51. Since the length of the flexible sleeve 47 remains substantially constant, the shearing head assembly remains spaced a constant distance from the anchor plate 46 along the push-pull unit. The shearing head assembly is thus anchored against relative reciprocating movement of the cable 48, rod 69 and rod 71. Accordingly, a full revolution of the shaft 31 caused by momentary actuation of the switch 80 is accompanied by one closing and re-opening of the shears. The swivel connections in the shearing head assembly enable the operator to freely turn the shears to any desired angle without the necessity of twisting the push-pull unit which may be particularly difficult to maintain in twisted position during actuation. It will be apparent that the shearing head assembly constitutes a light and compact unit. These attributes are particularly apparent when the present type of shearing head is compared to the shearing heads of the prior art which include fluid motors that have to be carried by the operator and which buck or jerk when actuated.

Many alternatives to the specific embodiment disclosed above are possible. For example, the reduction gearing between the output side of the clutch and the drive crank may be eliminated and the clutch employed as a true single revolution clutch (cutting action then being more rapid at a given engine speed), although it appears that the illustrated embodiment minimizes clutch wear and strain and appears preferable at the present time. Ac-

cordingly, the scope of the invention is not to be restricted to the details of the illustrated embodiment but is to be defined by the scope of the following claims.

What is claimed is:

5 1. Power lopping shears comprising a frame, a shaft
rotatably mounted on said frame, a crank arm on said
shaft, an anchor block fixedly supported on said frame,
a push-pull unit comprising an outer flexible sheath
capable of resisting substantial axial compression without
10 buckling, and an inner cable loosely received in said
sheath, one end of said sheath terminating in a sleeve,
means on said anchor block restraining said sleeve against
axial shifting with respect to said frame, one end of said
cable passing through said sleeve and extending toward
15 said crank arm, means connecting said one end of said
cable to said crank arm for reciprocation of said cable by
said crank arm, a shearing head assembly remote from
said frame, the opposite end of said sheath being fixed
to one end of said shearing head assembly, lopping shears
20 comprising a pair of scissors, one blade of said pair being
fixedly mounted on the opposite end of said shearing head
assembly, the opposite end of said cable having extension
means extending through said shearing head assembly
and operatively attached to the other blade of said pair,
25 drive linkage means to drive said shaft, said drive linkage
means comprising continuously driven means, clutch
means between said continuously driven means and said
shaft, solenoid means on said frame, and means operatively
connected to and controlled by said solenoid means
30 to engage said clutch means for one rotation of said shaft
upon actuation of said solenoid means and to disengage
said clutch means upon completion of said one rotation
in the absence of continued actuation of said solenoid
means, switch means on said shearing head assembly to
35 control actuation of said solenoid means, means operatively
connecting said switch means and said solenoid means,
said shearing head assembly comprising tube means,
said cable extension means extending axially through
40 said tube means, and swivel connections in said
shearing head assembly to enable swivelling movement
of said opposite end of said shearing head assembly with
respect to the portion of said push-pull unit extending
between said anchoring block and said shearing head
assembly.

45 2. Power lopping shears comprising a frame, a shaft
1 rotatably mounted on said frame, a crank arm on said
1 shaft, an anchor block fixedly supported on said frame,
1 a push-pull unit comprising an outer flexible sheath ca-
50 pable of resisting substantial axial compressive stresses
without buckling, and an inner cable loosely received in
said sheath, one end of said sheath terminating in a sleeve
rigidly fixed to said anchor block, one end of said cable
passing through said sleeve and extending toward said
crank arm, means connecting said one end of said cable
55 to said crank arm for reciprocation of said cable by said
crank arm, a shearing head assembly remote from said
frame, the opposite end of said sheath being fixed to one
end of said shearing head assembly, lopping shears com-
prising a pair of scissors, one blade of said pair being
60 fixedly mounted on the opposite end of said shearing head
assembly, the opposite end of said cable having
extension means extending through said shearing head
assembly and operatively attached to the other blade of
said pair, drive linkage means to drive said shaft, said
65 drive linkage means comprising continuously driven
means, clutch means between said continuously driven
means and said shaft, solenoid means on said frame, and
means operatively connected to and controlled by said
solenoid means to engage said clutch means for one ro-
70 tation of said shaft upon actuation of said solenoid
means and to disengage said clutch means upon comple-
tion of said one rotation in the absence of continued
actuation of said solenoid means, switch means on said
shearing head assembly to control actuation of said sole-
75 noid means, means operatively connecting said switch

means and said solenoid means, said shearing head assembly comprising tube means, said cable extension means extending axially through said tube means, and swivel connections in said shearing head assembly to enable swivelling movement of said opposite end of said shearing head assembly with respect to the portion of said push-pull unit extending between said anchoring block and said shearing head assembly.

3. Power lopping shears comprising a frame, a shaft rotatably mounted on said frame, a crank arm on said shaft, a push-pull unit comprising an outer flexible sheath capable of resisting substantial axial compression without buckling, and an inner cable loosely received in said sheath, one end of said sheath terminating in a sleeve, means on said frame restraining said sleeve against axial shifting with respect to said frame, one end of said cable passing through said sleeve and extending toward said crank arm, means connecting said one end of said cable to said crank arm for reciprocation of said cable by said crank arm, a shearing head assembly remote from said frame, the opposite end of said sheath being fixed to said shearing head assembly, lopping shears comprising a pair of scissors, one blade of said pair being fixedly mounted on said shearing head assembly, the opposite end of said cable having extension means extending through said shearing head assembly and operatively attached to the other blade of said pair, drive linkage means to drive said shaft, said shearing head assembly comprising tube means, said cable extension means extending axially through said tube means, and swivel connections in said shearing head assembly to enable swivelling movement of said opposite end of said shearing head assembly with respect to the portion of said push-pull unit extending between said anchoring block and said shearing head assembly.

4. Power lopping shears comprising a frame, a shaft rotatably mounted on said frame, a crank arm on said shaft, an anchor block fixedly supported on said frame, a push-pull unit comprising an outer flexible sheath capable of resisting substantial axial compression without buckling, and an inner cable loosely received in said sheath, one end of said sheath terminating in a sleeve, means on said anchor block restraining said sleeve against axial shifting with respect to said frame, one end of said cable passing through said sleeve and extending toward said crank arm, means connecting said one end of said cable to said crank arm for reciprocation of said cable by said crank arm, a shearing head assembly remote from said frame, the opposite end of said sheath being fixed to one end of said shearing head assembly, lopping shears comprising a pair of scissors, one blade of said pair being fixedly mounted on the opposite end of said shearing head assembly, the opposite end of said cable having extension means extending through said shearing head assembly and operatively attached to the other blade of said pair, drive linkage means to drive said shaft, said drive linkage means comprising continuously driven means, clutch means between said continuously driven means and said shaft, solenoid means on said frame, and means operatively connected to and controlled by said solenoid means to engage said clutch means for one rotation of said shaft upon actuation of said solenoid means and to disengage said clutch means upon completion of said one rotation in the absence of continued actuation of said solenoid means, switch means on said shearing head assembly to control actuation of said solenoid means, and means operatively connecting said switch means and said solenoid means.

5. Power lopping shears comprising a frame, a shaft rotatably mounted on said frame, a crank arm on said shaft, a push-pull unit comprising an outer flexible sheath capable of resisting substantial axial compressive stresses without buckling, and an inner cable loosely received in said sheath, one end of said sheath terminating in a sleeve rigidly mounted on said frame, one end of said

cable passing through said sleeve and extending toward said crank arm, means connecting said one end of said cable to said crank arm for reciprocation of said cable by said crank arm, a shearing head assembly remote from said frame, the opposite end of said sheath being fixed to said shearing head assembly, lopping shears comprising a pair of scissors, one blade of said pair being fixedly mounted on said shearing head assembly, the opposite end of said cable having extension means extending through said shearing head assembly and operatively attached to the other blade of said pair, drive linkage means to drive said shaft, said shearing head assembly comprising tube means, said cable extension means extending axially through said tube means, and swivel connections in said shearing head assembly to enable swivelling movement of said opposite end of said shearing head assembly with respect to the portion of said push-pull unit extending between said anchoring block and said shearing head assembly.

20 6. Power lopping shears comprising a frame, a shaft rotatably mounted on said frame, a crank arm on said shaft, an anchor block fixedly supported on said frame, a push-pull unit comprising an outer flexible sheath capable of resisting substantial axial compressive stresses without buckling, and an inner cable loosely received in said sheath, one end of said sheath terminating in a sleeve rigidly fixed to said anchor block, one end of said cable passing through said sleeve and extending toward said crank arm, means connecting said one end of said cable to said crank arm for reciprocation of said cable by said crank arm, a shearing head assembly remote from said frame, the opposite end of said sheath being fixed to one end of said shearing head assembly, lopping shears comprising a pair of scissors, one blade of said pair being fixedly mounted on the opposite end of said shearing head assembly, the opposite end of said cable having extension means extending through said shearing head assembly and operatively attached to the other blade of said pair, drive linkage means to drive said shaft, said drive linkage means comprising continuously driven means, clutch means between said continuously driven means and said shaft, solenoid means on said frame, and means operatively connected to and controlled by said solenoid means to engage said clutch means for one rotation of said shaft upon actuation of said solenoid means and to disengage said clutch means upon completion of said one rotation in the absence of continued actuation of said solenoid means, switch means on said shearing head assembly to control actuation of said solenoid means, and means operatively connecting said switch means and said solenoid means.

40 7. Power lopping shears comprising a frame, a shaft rotatably mounted on said frame, a crank arm on said shaft, a push-pull unit comprising an outer flexible sheath capable of resisting substantial axial compression without buckling, and an inner cable loosely received in said sheath, one end of said sheath terminating in a sleeve, means on said frame restraining said sleeve against axial shifting with respect to said frame, one end of said cable passing through said sleeve and extending toward said crank arm, means connecting said one end of said cable to said crank arm for reciprocation of said cable by said crank arm, a shearing head assembly remote from said frame, the opposite end of said sheath being fixed to said shearing head assembly, lopping shears comprising a pair of scissors, one blade of said pair being fixedly mounted on said shearing head assembly, the opposite end of said cable having extension means extending through said shearing head assembly and operatively attached to the other blade of said pair, and drive linkage means to drive said shaft.

50 8. Power lopping shears comprising a frame, a shaft rotatably mounted on said frame, a crank arm on said shaft, a push-pull unit comprising an outer flexible sheath capable of resisting substantial axial compressive stresses

without buckling, and an inner cable loosely received in said sheath, one end of said sheath terminating in a sleeve rigidly fixed to said frame, one end of said cable passing through said sleeve and extending toward said crank arm, means connecting said one end of said cable to said crank arm for reciprocation of said cable by said crank arm, a shearing head assembly remote from said frame, the opposite end of said sheath being fixed to said shearing head assembly, lopping shears comprising a pair of scissors, one blade of said pair being fixedly mounted on said shearing head assembly, the opposite

5

10

end of said cable having extension means extending through said shearing head assembly and operatively attached to the other blade of said pair, and drive linkage means to drive said shaft.
